INVENTOR:

Samuel D. Kimble

United States Patent Office.

SAMUEL D. KIMBLE, OF ALLEGHENY CITY, PENNSYLVANIA.

Letters Patent No. 83,174, dated October 20, 1868.

IMPROVED CARRIAGE-BRAKE.

The Schedule referred to in these Letters Patent and making part of the same.

To all whom it may concern:

Be it known that I, SAMUEL D. KIMBLE, of Allegheny City, in the county of Allegheny, and State of Pennsylvania, have invented certain new and useful Improvements in Self-Acting Speed-Regulator; and I do hereby declare that the following is a full, clear, and exact description thereof, reference being had to the accompanying drawings, and to the letters of reference marked thereon, which form a part of this specification.

My invention relates to devices used for regulating the speed of vehicles drawn by horse-power; and consists in providing a circular disk, to which is attached a notched wheel, both of which are affixed to the hub of wheels, by means of screws or such like devices; by also providing two levers, pivoted and parallel with the hind axle-tree, and so arranged, and of such a form that the ends near the hubs will catch in the notched wheel before described, and also will, when operated upon as hereinafter to be described, bear against the side face of the before-mentioned disk. These levers are operated upon by and are connected with two levers running parallel and on each side of the coupling pole of the vehicle, which levers are connected in any suitable manner with a right-angled lever, vibrating and pivoted to suitable bearings, attached also to the coupling-pole. A strap, chain, or any such like device, is connected with the upper portion or throw of the before-mentioned right-angled lever, to which chain are attached two ropes, or such like device or devices, which pass through a guide attached to the tongue of the wagon or vehicle, and pass around a pin affixed to the neck-yoke, and upwards to the horses' hames.

In the accompanying drawings—

Figure 1 is a plan of my self-acting speed-regulator as attached to the running gear of an ordinary wagon.

Figure 2 is a longitudinal section of the same.

Figure 3, a cross-section of the same.

Figure 4, elevation of some of the devices used.

A represents the hub of the wheel; A¹, the circular disk; A², the notched wheel; R, the hind axle-tree; B and B', the axle-levers; C and C', the coupling-pole levers; D, the right-angled lever; D¹ and D², the bearings; E, the strap; E¹ and E², the ropes; F, the guide; G, the neck-yoke; G¹ and G², the neck-yoke pins.

The mode of operating my devices is as follows, viz:

The vehicle, when descending an incline, will have a tendency to crowd down on the horses' flanks, on which, beasts naturally draw upward their heads and hold back, to prevent themselves from being overbalanced or thrown down. This act operates and puts in motion my devices, as the ropes E¹ and E², being connected with the horses' hames, and furthermore, being directly connected with the right-angled lever D by means of the strap E, any such action on the part of the horse will pull over the right-angled lever D, in such a manner that it will operate upon the levers C and C', and at the same time, and by the same operation, operate upon the levers B and B', pressing their ends against the notched wheel A², and also, laterally, against the face of the disk A¹, thus locking the wheels, and making the descent comparatively easy. Directly the vehicle gets on level ground, the devices operate reversely, and the levers B and B' are withdrawn from contact with the disk A¹, and notched wheel A².

As self-acting brakes or speed-regulators have been heretofore made, the locking is performed by means of rubbers, which bear on the periphery of the wheel, and are also cumbersome, expensive, and, by reason of many joints, constantly wanting repairs.

By my devices the wheels are locked more securely, more permanently, and by also a very simple arrangement, which insures success.

Having thus described the nature, construction, and operation of my self-acting speed-regulator, What I claim, and desire to secure by Letters Patent, is—

The disk A and notched wheel A², with the levers B and B', when connected with the hub A and axle-tree R, as described, in combination with the crank-lever D, levers C and C', strap E, cords E¹ and E², and neck-yoke G with its devices, when constructed, combined, and arranged, substantially as herein described and for the purpose set forth.

In testimony that I claim the foregoing as my own, I affix my signature in presence of two witnesses.

SAMUEL D. KIMBLE.

Witnesses:

PERCEVAL BECKETT,
EDWARD WINTER.
